UNITED STATES PATENT OFFICE.

KURT SJOESTROEM, OF CHICAGO, ILLINOIS.

DESIGN FOR A COMBINED CIGAR CUTTER, ASH TRAY, AND LIGHTER.

Application filed September 4, 1928. Serial No. 28,032. Term of patent 3½ years.

To all whom it may concern:

Be it known that I, KURT SJOESTROEM, a citizen of the United States, residing at Chicago, in the county of Cook and State of Illinois, have invented a new, original, and ornamental Design for a Combined Cigar Cutter, Ash Tray, and Lighter, of which the following is a specification, reference being had to the accompanying drawing, forming part thereof.

The figure is a perspective view of a combined cigar cutter, ash-tray, and lighter showing my new design.

I claim:

The ornamental design for a combined cigar cutter, ash-tray, and lighter as shown.

KURT SJOESTROEM.
